LATCH

Gordon E. Roedding, Grand Rapids, Mich., assignor to Grand Rapids Brass Company, Grand Rapids, Mich., a corporation of Michigan

Application October 10, 1934, Serial No. 747,680

11 Claims. (Cl. 292—126)

The present invention relates to latches for the swingable door closures of refrigerators and the like; and its object is, generally, to provide an improved device of this character; and particularly, to provide such a device having a latch bolt moved into and held in latching position (operative engagement with its "strike" or keeper) by sufficient force to tightly close the closure, but which may be withdrawn from such engagement by comparatively little force; and further, to provide improved means for mounting the latch bolt and for operating the same.

These and any other and more specific objects hereinafter appearing are attained by, and the invention finds preferable embodiment in, the illustrative latch structure particularly described in the body of this specification and illustrated by the accompanying drawing, in which:

Figure 1 is an elevational view of the free edge 20 of a swingable closure with a latch structure mounted thereon shown partially in vertical section taken on line 1—1 of Figure 2, the door frame or jamb with the keeper or "strike" being shown sectioned on the same line;

Figure 2 is a vertical sectional view of said structure taken on line 2—2 of Figure 1;

Figure 3 is a horizontal sectional view of the parts shown in Figure 1 taken on line 3—3 of that view;

Figure 4 is a vertical sectional view of portions of certain parts shown in Figure 1 taken on line 1—1 of Figure 2 but showing said parts in their position when the latch bolt is released and the closure is being opened;

Figure 5 is a similar view thereof but showing the parts in their position when the open closure is nearly closed.

In the embodiment of the invention illustrated by the drawing, a latch structure is shown comprising a casing 1 mounted by screws 2 on the free edge 3 of a swingably mounted closure 4 and containing a latch bolt 5 projecting through the casing's opening 6 for engagement with its keeper 7 mounted by screws 8 on the face 9 of the door frame or jamb 10 of the refrigerator or the like. This bolt 5 is a lever having a pair of fulcruming members, the pins 11, 12 spaced in the bolt's longitudinal direction, the pin 11 extending through the middle portion of the lever bolt between its outer arm 13 which engages the keeper and its inner arm 14, and the pin 12 extending through said inner arm. These fulcruming members, the pins 11, 12 normally bear on a pair of fulcrum 15, 16 respectively which are vertically movable relatively to each other (that is, fulcrum

15 is stationary and fulcrum 16 is movable), the fulcrum 15 being the lower end of a pair of approximately vertical slots 17 in the sides 18 of the casing, and the fulcrum 16 being the horizontal under side of the curved cam slots 19 and forming an initial dwell at their outer ends, these slots being formed in the parallel side flanges 20 of the operating lever handle 21 pivotally mounted at 22 on the casing's said sides, this handle being urged by a coiled spring 23 to its normal position shown in Figures 1 and 2.

A stirrup 24 carried by the pin 11 is urged downwardly, by a stiff spring 25 pressing between its middle portion 26 and a stop or shelf 27 on the casing, to move the stirrup, pin 11 and the latch bolt into the bolt's latching position shown in Figure 1 and hold the same in said position, the closure being tightly closed by the wedging or camming action of the inclined surface 29 of the latch's arm 13 engaging the keeper as seen in Figure 1, resilient packing members indicated at 30 desirably surrounding the inner side of the closure adjacent its edges to seal the refrigerator air tight.

In this normal position of the parts wherein the closure is held closed by the latch bolt, the bolt's inner arm 14 (desirably provided with an antifriction roll 31 as indicated) is supported on the fulcrum or dwell 16, the handle 21 being in its normal position, all as shown in Figure 1. 30

When it is desired to open the closure, the handle is swung outwardly, whereby the fulcrum or dwell 16 is moved in a direction transaxially of the pin 12, so that the roll 31 passes off of said fulcrum dwell and is moved farther into the slot 19, and its cam upper side 32 traveling on this roll forces arm 14 of the bolt downwardly and its arm 13 upwardly out of latching engagement with the keeper, the bolt in this movement turning on the fulcrum 15, the bottom of slots 17. 40 The parts are now in the position seen in Figure 4. When the closure is open and the handle is released its spring 23 returns the handle to its said normal position, this action camming the roll 31 out of the inner portion of slot 19 and 45 onto the fulcrum dwell 16 so that the parts are again in the position shown in Figure 1 except that the closure is open.

When the closure is then closed by slamming it shut, the curved forward under edge 33 of the bolt's arm 13 riding up on the edge 34 of the keeper raises the bolt to the position seen in Figure 5 against the pressure of spring 25, so that when the point 35 of the bolt passes the keeper the spring 25 suddenly turns the bolt to 55

latching engagement with the keeper shown in Figure 1.

It will be seen that the unlatching movement of the bolt is brought about by the relative movement of the two fulcrums 15, 16 on which the bolt's fulcruming members 11, 12 respectively turn, and that the spring 25 is not affected by said movement, so that although this spring may be very stiff for engaging the bolt with its keeper, the bolt is movable out of such engagement by slight force applied to the operating handle 21.

It will also be seen that each of the fulcruming members 11, 12 is movable relatively to its fulcrum 15 or 16 into and out of supported position thereon and that such movement of one of said members is at approximately right angles to such movement of the other member.

The invention being intended to be pointed out in the claims, is not to be limited to or by details of construction of any particular embodiment thereof illustrated by the drawing or hereinbefore described.

I claim:

1. A latch structure comprising: a lever latch bolt having spaced fulcruming members; fulcrums for said members respectively, one of the members being mounted for reversible movement to supported position on its fulcrum in a direction parallel with the bolt's movement to its latching position; a spring urging said member in its said movement and the bolt to latching position; an operating unitary handle carrying the other fulcrum in a position supporting the other member in the normal position of the handle and in the latching position of the bolt, the handle being movable from its normal position for moving said other fulcrum from its said supporting position; means operable by the handle in its said movement for moving said other member about the axis of the first-mentioned member to thus turn the bolt on the first-mentioned fulcrum from latching position, the handle being reversely movable to normal position for moving said other member reversely to thus turn the bolt reversely and for moving said other fulcrum into its said supporting position, the bolt in its last-mentioned position being turned on said other fulcrum and the first-mentioned member being reversely moved against the pressure of the spring from supported position on the first-mentioned fulcrum by the movement of the bolt's latching arm caused by its engagement with the bolt's keeper in the movement of the closure to closed position.

2. A latch structure comprising: a lever latch bolt having spaced fulcruming members; fulcrums for said members respectively, one of the members being mounted for reversible movement to supported position on its fulcrum in a direction parallel with the bolt's movement to its latching position; a spring urging said member in its said movement and the bolt to latching position; an operating unitary handle carrying the other fulcrum in a position supporting the other member in the normal position of the handle and in the latching position of the bolt, the handle being movable from its normal position for moving said other fulcrum from its said supporting position; means operable by the handle in its said movement for moving said other member about the axis of the first-mentioned member to thus turn the bolt on the first-mentioned fulcrum from latching position, the handle being reversely movable to normal position

for moving said other member reversely to thus turn the bolt reversely and for moving said other fulcrum into its said supporting position, the bolt in its last-mentioned position being turned on said other fulcrum and the first-mentioned member being reversely moved against the pressure of the spring from supported position on the first-mentioned fulcrum by the movement of the bolt's latching arm caused by its engagement with the bolt's keeper in the movement of the closure to closed position; a spring urging the handle to normal position.

3. A latch structure comprising: a lever latch bolt having spaced fulcruming members; relatively movable fulcrums for said members respectively; a spring pressing one of the members on its fulcrum and the bolt to the bolt's latching position; an operating handle carrying the other fulcrum and in normal position supporting the other member thereon, the handle being movable from normal position for moving said other fulcrum transaxially from such supporting position and having means engaging said other member for moving the same about the axis of the first-mentioned member to thus turn the bolt on the first-mentioned fulcrum from latching position and movable to normal position for moving said other member by said means reversely to thus turn the bolt to latching position and moving said other fulcrum to position supporting said other member.

4. A latch structure comprising: a lever latch bolt having spaced fulcruming members; relatively movable fulcrums for said members respectively; a spring pressing one of the members on its fulcrum and the bolt to the bolt's latching position; an operating handle carrying the other fulcrum and in normal position supporting the other member thereon, the handle being movable from normal position for moving said other fulcrum transaxially from such supporting position and having means engaging said other member for moving the same about the axis of the first-mentioned member to thus turn the bolt on the first-mentioned fulcrum from latching position and movable to normal position for moving said other member by said means reversely to thus turn the bolt to latching position and moving said other fulcrum to position supporting said other member; a spring urging the handle to normal position.

5. In a latch structure for a swingable closure: a casing having a slot forming a fulcrum; a lever latch bolt having a pin turnable and transaxially slidable in the slot; a stirrup carried by the pin; a spring between the stirrup and a stop on the casing and pressing the pin to one end of the slot and thus urging the bolt to latching position; a pivotally mounted operating handle having a curved cam slot receiving an arm of the bolt, the slot having an initial dwell supporting said arm in the handle's normal position, the handle being turnable from normal position for moving said dwell from such supporting position and for moving the arm about the axis of the pin to thus turn the bolt about said axis from latching position, the handle being movable to normal position for moving the arm by the cam slot reversely, turning the bolt to latching position and moving the dwell to position supporting the arm; a spring urging the handle to normal position.

6. A latch structure comprising: a lever latch bolt having spaced fulcruming members; relatively movable fulcrums for said members respectively; a spring urging one of the members on

its fulcrum and the bolt in the bolt's latching direction; a pivotally mounted handle having a curved cam slot receiving the other member, the slot having an initial dwell forming the other fulcrum and in the handle's normal position supporting said other member thereon, the handle being turnable from normal position for moving said dwell fulcrum transaxially of the member thereon from such supporting position and for moving said other member about the axis of the first-mentioned member to thus turn the bolt on the first-mentioned fulcrum from latching position, the handle being turnable to normal position for moving said other member reversely by the cam slot to thus turn the bolt to latching position and for moving the dwell fulcrum to its position supporting said other member.

7. A latch structure comprising: a casing having a slide bearing extending in the direction of the hereinafter-mentioned bolt's movement to latching position; a lever latch bolt in the casing having spaced fulcruming members, one of said members being slidable in said bearing; relatively movable fulcrums for said members respectively, one of said fulcrums being the end of said bearing; a spring urging said member onto its said fulcrum and the bolt to latching position; a pivotally mounted handle having a curved cam slot receiving the other member, the slot having an initial dwell forming the other fulcrum and in the handle's normal position supporting said other member thereon, the handle being turnable from normal position for moving said dwell fulcrum transaxially of the member thereon from such supporting position and for moving said other member about the axis of the first-mentioned member to thus turn the bolt on the first-mentioned fulcrum from latching position, the handle being turnable to normal position for moving said other member reversely by the cam slot to thus turn the bolt to latching position and for moving the dwell fulcrum to its position supporting said other member.

8. A latch structure comprising: a casing having a slide bearing extending in the direction of the hereinafter-mentioned bolt's movement to latching position; a lever latch bolt in the casing having spaced fulcruming members, one of said members being slidable in said bearing; relatively movable fulcrums for said members respectively, one of said fulcrums being the end of said bearing; a spring urging said member onto its said fulcrum and the bolt to latching position; a pivotally mounted handle having a curved cam slot receiving the other member, the slot having an initial dwell forming the other fulcrum and in the handle's normal position supporting said other member thereon, the handle being turnable from normal position for moving said dwell fulcrum transaxially of the member thereon from such supporting position and for moving said other member about the axis of the first-mentioned member to thus turn the bolt on the first-mentioned fulcrum from latching position, the handle being turnable to normal position for moving said other member reversely by the cam slot to thus turn the bolt to latching position and for moving the dwell fulcrum to its position supporting said other member; a spring urging the handle to normal position.

9. A latch structure comprising: a casing having a slide bearing extending in the direction of the hereinafter-mentioned bolt's movement to latching position; a lever latch bolt in the casing having spaced fulcruming members, one of said

members being slidable in said bearing; relatively movable fulcrums for said members respectively, one of said fulcrums being the end of said bearing; a spring urging said member onto its said fulcrum and the bolt to latching position; a pivotally mounted handle having a curved cam slot receiving the other member, the slot having an initial dwell forming the other fulcrum and in the handle's normal position supporting said other member thereon, the handle being turnable from normal position for moving said dwell fulcrum transaxially of the member thereon from such supporting position and for moving said other member about the axis of the first-mentioned member to thus turn the bolt on the first-mentioned fulcrum from latching position, the handle being turnable to normal position for moving said other member reversely by the cam slot to thus turn the bolt to latching position and for moving the dwell fulcrum to its position supporting said other member, the bolt in its last-mentioned position being turned on said other fulcrum and the first-mentioned member being reversely moved against the pressure of the spring from supported position on the first-mentioned fulcrum by the movement of the bolt's latching arm caused by its engagement with the bolt's keeper in the movement of the closure to closed position.

10. A latch structure comprising: a casing having a slide bearing extending in the direction of the hereinafter-mentioned bolt's movement to latching position; a lever latch bolt in the casing having spaced fulcruming members, one of said members being slidable in said bearing; relatively movable fulcrums for said members respectively, one of said fulcrums being the end of said bearing; a spring urging said member onto its said fulcrum and the bolt to latching position; a pivotally mounted handle having a curved cam slot receiving the other member, the slot having an initial dwell forming the other fulcrum and in the handle's normal position supporting said other member thereon, the handle being turnable from normal position for moving said dwell fulcrum transaxially of the member thereon from such supporting position and for moving said other member about the axis of the first-mentioned member to thus turn the bolt on the first-mentioned fulcrum from latching position, the handle being turnable to normal position for moving said other member reversely by the cam slot to thus turn the bolt to latching position and for moving the dwell fulcrum to its position supporting said other member, the bolt in its last-mentioned position being turned on said other fulcrum and the first-mentioned member being reversely moved against the pressure of the spring from supported position on the first-mentioned fulcrum by the movement of the bolt's latching arm caused by its engagement with the bolt's keeper in the movement of the closure to closed position; a spring urging the handle to normal position.

11. A latch structure comprising: a lever latch bolt having spaced fulcruming members; relatively movable fulcrums for said members respectively, each of the members having a movement to and from supported position on its fulcrum, such movements of the respective members relative to their respective fulcrums being at approximately right angles to each other; a spring urging one of the members to supported position on its fulcrum and the bolt to latching position; an operating handle carrying the other

fulcrum and in normal position supporting the other member thereon, the handle being movable from normal position for moving said other fulcrum from such supporting position and having 5 means engaging said other member for moving the same about the axis of the first-mentioned member to thus turn the bolt on the first-mentioned fulcrum from latching position, and movable to normal position for moving said other 10 member by said means reversely to thus turn the bolt to latching position and moving said other

fulcrum to position supporting said other member, the bolt in its last-mentioned position being turned on said other fulcrum and the first-mentioned member being reversely moved against the pressure of the spring from supported position on the first-mentioned fulcrum by the movement of the bolt's latching arm caused by its engagement with the bolt's keeper in the movement of the closure to closed position. 5

GORDON E. ROEDDING.
